UNITED STATES PATENT OFFICE.

CHRISTIAN A. BUSCHAM, OF IRVINGTON, NEW JERSEY, ASSIGNOR TO C. A. BUSCHAM MFG. CO., OF IRVINGTON, NEW JERSEY.

VANITY BOX OF WATCHCASE TYPE.

Application filed September 21, 1925. Serial No. 57,641.

This invention relates to vanity boxes and has special reference to a box for containing face powder, rouge and the like such boxes commonly known as compacts, of 5 watch case type.

One object of the invention is to improve the general construction of the compact.

A second object of the invention is to provide a novel hinge arrangement for boxes 10 of this class.

A third object of the invention is to provide a novel arrangement of the rouge box and its cover.

A fourth important object of the invention 15 is to provide novel means for holding the rouge box in the outer case.

A fifth important object of the invention is to provide a novel arrangement of snap for holding the rouge box cover closed.

With the above and other objects in view as will be hereinafter apparent, the invention consists in general of certain novel details of construction and combinations of parts hereinafter fully described, illustrated 25 in the accompanying drawings and specifically claimed.

In the accompanying drawings like characters of reference indicate like parts in the several views, and:

Figure 1 is a plan view of the invention with the cover opened.

Figure 2 is a section on the line 2—2 of Figure 1 but showing the rouge box opened.

Figure 3 is an enlarged detail section on 35 the line 3—3 of Figure 1.

Figure 4 is a detail to an enlarged scale showing the hinge arrangement and one of the rouge box retaining members.

Figure 5 is a detail to enlarged scale 40 showing one of the spring clips used for holding the cover closed.

Figure 6 is a section on the line 6—6 of Figure 2.

Figure 7 is a detail section on the line 7—7 45 of Figure 3.

Figure 8 is a detail view showing the inside of the box and disclosing the spring tongues for holding the cover of the rouge box.

In the present embodiment of the invention there is shown a box of the ordinary watch case form having a body 10 provided around its upper edge with an angled portion 11 forming a bead, a flange 12 extend-

ing upwardly from this bead. At one point 55 of its periphery, this flange 12 is extended upwardly as at 13, and rolled as at 14 to form a tube wherethrough passes the straight portion of a hinge wire 15 which extends around beneath the shoulder 16 of 60 the top 17. This top has a flange 18 which, when top is closed on the bottom, fits within the flange 12. The hinge wire 15 extends each way from the flange about quarter way around the cover and there has an outwardly 65 bent end 19 which passes through a suitable aperture 20 formed in the top of cover 17 just below the shoulder 16. With this arrangement the hinge wire reinforces that portion of the cover adjacent the hinge. 70 Seated in the body 10 is the rouge box and this consists of a sheet of metal stamped to provide a central portion 21 of general cylindrical shape, the portion being slightly shouldered as at 22 to form retaining means 75 for a spring ring 23, which latter serves to hold the rouge pad in position. Around this central portion is an outer wall 24 having at intervals upwardly extending portions 25 which there extend up to the groove formed 80 by the bead 11 and are bent outwardly to fit in said groove and retain the rouge box in place. These portions may also be punched out as at 26 from the inside of the box so as to lock with the body 10 and prevent rotation of the rouge box. At one side 85 of the rouge box the outer flange 24 is extended upwardly and rolled as at 27 to form hinge lugs. The rouge box top consists of a plate of metal 28 which is bent over to retain a bezel 29 which holds a mirror 30 in position. One portion of this bezel is rolled 90 as at 31 to form a complementary part of the cover hinge, an ordinary wire pintle being used to connect the parts 27 and 31. 95 Opposite the hinge of the rouge box the outer flange 24 is provided with a pair of spring clips 32 which are so spaced as to readily permit the thumb nail to be inserted between them and the rouge box top to 100 open such box and it is to be noted that one of the extensions 25 is, as shown in Figure 8 located between these two spring tongues to hold the latter firmly in position in the body 10.

With this construction it will be obvious that the box may be made of very thin metal while the hinge arrangement is of such

strength and the box so reinforced that collapse or other injury will not take place in ordinary use.

There has thus been provided a simple and efficient device of the kind described and for the purpose specified.

It is obvious that minor changes may be made in the form and construction of the invention without departing from the spirit thereof. It is not, therefore, desired to confine the invention to the exact form herein shown and described, but it is desired to include all such as properly come within the scope claimed.

Having thus described the invention, what is claimed as new, is:

1. In a box of the class described, a box body having a peripheral wall provided with a groove on the interior extending around the wall parallel to the edge, a rouge receptacle having an annular outer wall fitting against the peripheral wall of the box body and provided with upwardly extending portions having their ends engaged in said groove to retain the rouge receptacle in place, said rouge receptacle having an inner annular wall forming a substantially cylindrical rouge pocket, a cover for said rouge pocket hinged to the outer wall of the rouge receptacle, and cover holding spring fingers disposed on said outer wall opposite the hinge.

2. In a box of the class described, a box body having a peripheral wall provided with a groove on the interior extending around the wall parallel to the edge, a rouge receptacle having an annular outer wall fit-

ting against the peripheral wall of the box body and provided with upwardly extending portions having their ends engaged in said groove to retain the rouge receptacle in place, said rouge receptacle having an inner annular wall forming a substantially cylindrical rouge pocket, a cover for said rouge pocket hinged to the outer wall of the rouge receptacle, and cover holding spring fingers disposed on said outer wall opposite the hinge.

3. In a box of the class described, a box body having a peripheral wall provided with a groove on the interior extending around the wall parallel to the edge, a rouge receptacle having an annular outer wall fitting against the peripheral wall of the box body and provided with upwardly extending portions having their ends engaged in said groove to retain the rouge receptacle in place, said rouge receptacle having an inner annular wall forming a substantially cylindrical rouge pocket, a cover for said rouge pocket hinged to the outer wall of the rouge receptacle, and cover holding spring fingers disposed on said outer wall opposite the hinge, one of said upwardly extending portions of the outer wall being positioned between said spring fingers to prevent rotation of the rouge receptacle.

In testimony whereof I affix my signature.

CHRISTIAN A. BUSCHAM.
